UNITED STATES PATENT OFFICE.

JOSEPH LANHAM CONWAY, OF SIOUX CITY, IOWA.

DESIGN FOR A BOX-LID SUPPORT.

SPECIFICATION forming part of Design No. 29,643, dated November 8, 1898.

Application filed October 11, 1898. Serial No. 693,265. Term of patent 14 years.

To all whom it may concern:

Be it known that I, JOSEPH LANHAM CONWAY, of Sioux City, in the county of Woodbury and State of Iowa, have invented and produced a new and original Design for a Box-Lid Support, of which the following is a full, clear, and exact description.

Reference is to be had to the accompanying drawings, forming a part of this specification, in which similar characters of reference indicate corresponding parts in all the figures.

Figure 1 is a perspective view of a box-lid support, showing my design. Fig. 2 is a front elevation of the same. Fig. 3 is a rear elevation of the same, and Fig. 4 is an edge view of the same.

The design in its entirety consists of a front

plate A, one side of which terminates in the back flap B, extending to the rear of the front plate A as a doubled-up extension thereof, 20 the lower edge of the flap terminating in an arm C, extending at an obtuse angle to the back flap B and the front plate A.

The leading feature of my design consists in the front flap A, having a doubled-up extension, and an arm leading from the lower edge of the back flap at angles thereto.

I claim—

The design for a box-lid support, as herein shown and described.

JOSEPH LANHAM CONWAY.
